UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING MACHINE.

Original application filed March 13, 1924, Serial No. 699,056. Divided and this application filed June 3, 1925. Serial No. 34,674.

My invention relates to mining machines. An object of my invention is to provide an improved mining machine. Another object of my invention is to provide an improved mining machine having improved feeding mechanism. A third object of my invention is to provide an improved mining machine having improved controlling mechanism and adapted either to cut a kerf continuing the bottom, or a kerf a substantial distance above the bottom. A still further object of my invention is to provide an improved mining machine having improved feeding mechanism and improved controlling mechanism for said feeding mechanism. Yet another object of my invention is to provide an improved mining machine having improved feed controlling mechanism and means whereby the same may be readily controlled from either side during cutting in either direction relative to a face. Other objects of my invention will hereafter more fully appear.

This is a division of my copending application Serial No. 699,056, filed Mar. 13, 1924.

In the accompanying drawings I have shown for purposes of illustration one form which my invention may assume in practice.

In these drawings,—

Fig. 1 is a plan view of a mining machine constructed in accordance with the illustrative embodiment of my invention.

Fig. 2 is a side elevation of such a mining machine.

Fig. 3 is a detail sectional view through mechanism employed for holding a guiding sprocket in its adjusted position.

Fig. 4 is a side view of the rear end of the machine shown in Fig. 2, but from the opposite side.

Fig. 5 is a view in side elevation of the illustrative embodiment of my machine cutting with the bar a substantial distance above the bottom.

Fig. 6 is a horizontal longitudinal section through the feeding mechanism, the section being taken substantially on line 6—6 of Fig. 2, but with the machine facing in the opposite direction.

Fig. 7 is an enlarged detail of a clutch operating mechanism, the view being a section on the line 7—7 of Fig. 6.

Fig. 8 is a central vertical section on the 55 line 8—8 of Fig. 6.

Fig. 9 is a vertical section on the line 9—9 of Fig. 6.

Fig. 10 is a horizontal section on the line 10—10 of Fig. 9 showing the clutch operating means.

In the form of my invention presented for purposes of illustration I have shown a mining machine of the so-called room and pillar type, which comprises a frame generally designated 1, herein made up of a plurality of elements bolted together and providing opposite plane surfaces 2 and 3, either of which may support the mining machine during sliding movement of the latter over a 70 mine bottom. Adjacent and parallel to the plane of the surface 2 is a forwardly projecting cutter bar 4 provided with a circulating cutter chain 5 which carries cutter bits 6 of usual form, operative when the bar 75 is presented to the coal to cut a kerf therein. By reason of the disposition of the bar 4, it will be apparent that when the machine is sliding upon the surfaces 2 a kerf will be cut which will serve to extend the bottom, 80 while if the machine is inverted and used with the surface 3 engaging the bottom during cutting, a kerf a substantial distance above the bottom will be produced. For the purpose of moving the machine during 85 feeding and at other times I employ flexible feeding means 8, having during cutting across the face oppositely extending flexible portions 9 and 10 and adapted to be variously reaved depending upon the results desired. It will be understood that suitable guiding means are provided to cooperate with this flexible feeding means to position the same properly relative to the machine 90 in order that the latter may be propelled in 95 the desired way and it will be observed further that suitable feed operating members, herein designated 11 and 12, each of which is adapted to serve as a feed operating or as a take-up member depending upon the direction of cut or the position of the machine, are provided to cooperate with the flexible portions mentioned. The members 11 and 12 are coaxial and are of such construction 100 as to cooperate with the links of a chain, that being the form of flexible feeding means 105 employed for purposes of illustration herein.

The machine frame includes a motor 15 of the reversible type and also includes motor operated cutter chain driving mechanism and feed operating mechanism. The motor 5 armature shaft 16 carries at its rear end a bevel pinion 17 journaled at 18 in a bearing carried by a projecting portion 19 of the motor frame. The pinion 17 drives a gear 20. The gear 20 is keyed at 21 to a shaft 22 which rotates upon a vertical axis. The shaft 22 is journaled at its opposite ends in bearings 23 and 24 and carries below the bevel gear 20 a spur pinion 25 which drives a large spur gear 26 rotating upon a vertical axis. The gear 26 is journaled at 27 in a suitable manner upon the frame and is coaxial with the cutter chain driving sprocket 28 and with a shaft 30 which is keyed thereto at 31 and which carries a pinion 32 at its upper end. A split ring 33 cooperates with the key in maintaining the shaft 30 in fixed relation to the gear 26. The cutter chain driving sprocket 28 has an inwardly projecting flange 35 having clutch teeth 36 thereon 25 and is journaled on suitable bushings 37 and 38 on members 39 and 40. The member 39 is held by a permanent clutch 41 to the gear 26 and is also provided with clutch teeth 42 adapted to be connected to the clutch teeth 35 by a movable clutch element 43. The member 40 is journaled at 45 upon a removable bottom plate section 46 and is provided with teeth engaging with corresponding teeth upon the portion 47 of the member 30, the toothed engagement being indicated at 48. The member 46 is maintained in place by studs 49 mounted in a circular plate 50. Concentric with the shaft 30 is a vertically movable shaft 51 having a reduced portion 52 surrounded by spaced washers 53 and 54. Between the latter, washer members 55 and 56 having openings traversed by the reduced portion 52 are disposed. A nut 57 holds the parts 53, 54, 55 and 56 assembled upon the shaft 51 and the members 55 and 56 cooperate to form a groove 58 which provides a bearing for a flange 59 upon the interior of the clutch member 43. The shaft 51 at its upper end is cut away at 61 to prevent interference with the adjacent mechanism and is traversed by an opening 62 which is entered by a lever 63 mounted upon a shaft 64. The shaft 64 at its opposite ends carries slotted arms 65 and 66 which are keyed thereto and held by a suitable threaded nuts 67. With these slotted arms means for effecting oscillation of the shaft 64 cooperates, this means including a shaft 68 having an eccentrically disposed pin 69 adapted to fit in the slots of the arms and on rotation of the shaft 68 to cause rocking of the shaft 64. The shaft 68 is journaled in a member 71 which is in the form of a dummy sprocket which may be used to exert a guiding function if desired on the flexible feeding member. This sprocket is held to the frame by a machine screw 72 and contains recesses 73 adapted to receive a spring pressed plunger or locking pin 74 upon an operating handle 75. The mechanism including the parts 68 to 75 may be placed at either side of the machine frame, a suitable opening 76 normally closed by a plate 77 being provided at the right hand side of the machine, and upon transfer of the controlling members for the shaft 64 to the right side of the machine, the plate 77 will be transferred to the left hand side to close the corresponding opening through which the mechanism had previously projected. It will be evident from the description so far that the operation of the cutter chain driving sprocket may be controlled from either side of the machine by manipulation of the handle 75 causing oscillation of the shaft 64 with resultant swinging movement of the lever 63 and raising and lowering of the shaft 51 and clutch element 43, raising of the latter serving to connect the cutter chain driving sprocket for driving through the element 39, permanent clutch 41, gear 26, pinion 25, shaft 22, bevel gear 20 and bevel pinion 17 upon the armature shaft 16 of the motor 15. The direction in which the motor rotates will determine the direction of rotation of the cutter chain driving sprocket 95 so that in cutting in opposite directions across a face, the motor will necessarily be reversed.

The feeding mechanism may now be taken up. The members 11 and 12 are concentric with a hollow transversely extending shaft 80 which extends completely from one side of the machine to the other. The shaft member 80 is not connected in any way to the members 11 and 12, but the latter are freely 103 rotatable relative to this shaft. A pair of worms 81 and 82 are journaled for rotation upon vertical axes lying in a plane parallel to the axis of the shaft 80, one of these worms, herein the worm 82, having 110 a substantially steeper pitch than the other so that it effects a faster drive of the element driven thereby than is effected by the worm 81. The worm 81 is mounted upon a built-up shaft 83 integral with whose upper portion a driving gear 84 is formed. The worm 82 is similarly supported and carries a gear 85 meshing with the gear 84 upon the upper portion of its two-part shaft 86 while the lower part of its two-part shaft carries a gear 87. The relative speeds of the worms can obviously be varied by substituting different gear combinations for the gears 84, 85. The shafts 83 and 86 are journaled in suitable ball bearings 88. The pinion 32 constantly meshes with and constitutes a driving element for the gear 87 and accordingly both worms 81 and 82 are constantly rotated during operation of the motor 15, though as illustrated, they rotate 125 130

in opposite directions. The worm 81 meshes with worm wheel 91 and the worm 82 with the worm wheel 92. The worm wheels 91 and 92 are respectively keyed as at 93 and 5 94 to sleeve-like members 95 and 96, which members are supported upon ball bearings generally designated 97. The ball bearings 97 surround sleeves 99 and 100 journaled upon the shaft 80. The sleeves 99 and 100 10 carry bevel gears 101 and 102 with which there cooperate two bevel gears 103 mounted on spindles 104 carried on a member 105 which is mounted upon the shaft 80. As the section of Fig. 6 is taken on lines at 15 right angles to each other but one of these pinions shows. The member 105 is slotted at right angles to the plane of the axes of the gears 103 and there is slidable therein a clutch provided with clutch teeth 106 and 20 107 at its opposite sides which are adapted to mesh with corresponding teeth 108 and 109 on the sleeves 95 and 96 respectively. Owing to the nature of the section, only 25 half of the clutch shows in Fig. 6. It will be apparent that as the teeth 106 and 107 are moved in opposite directions longitudinally of the shaft 80, the member 105 will be connected in driven relation with one or the other of the gears 91, 92 with the result 30 that this mechanism will cause bodily rotation of the pinions 103. The clutch teeth 106 and 107 are adapted to be shifted longitudinally by means of a cross member 110 extending through a slot 111 in the shaft 80 35 and cooperating with a recess 112 in a rod 113 extending through the hollow shaft 80. This rod is adapted to be moved in opposite directions by a handle 114 which is threadedly connected with the rod and may 40 be placed in engagement with the latter through either end of the shaft 80. It is also to be observed that the sleeves 99 and 100 constitute mountings for the sprockets 11 and 12 and that these sprockets are connected to these sleeves in non-rotative relation. It should further be noted that the 45 sleeves 99 and 100 carry keyed thereto brake drum elements 115 and 116, with which brake bands 117 and 118 respectively cooperate, these brake bands being supported by stationary mountings 119 and 120. These bands have at their free ends mechanism for varying their tension.

Observing Fig. 7 it will be noted that the 55 extremities of the band 117 carry a pair of pins 121 and 122 upon which a pair of arms 123 and 124 are pivotally mounted. Bars 125 are carried by a rod 137 and are pivotally connected as at 126 and 127 to the 60 arms 123 and 124 so as to provide fulcras for these arms. The arms 123 and 124 have oppositely inclined surfaces 128 and 129 with which rollers 130 and 131 are adapted to cooperate and on longitudinal movement to effect pivoting of the arms about the

pivot points 126 and 127. The rollers 130 and 131 are carried in slots 132 in sleeves 133 which are internally threaded as at 134. The construction of the mechanism cooperating with the brake band 118 is similar, but 70 opposite, to that described in connection with the brake band 117. Screws 135 and 136 engage the sleeves 133 forming parts of the operating mechanism for the brake bands 117 and 118. The screws 135 and 136 75 surround the rod 137 and are supported upon sleeves 138 and 139 which are journaled in the sides of the frame. To effect operation of these sleeves and accordingly of the screws a plurality of operating 80 handles 140 and 141 are provided. The handle 140 is provided with a shaft 142 which is adapted to be clutched and pinned as at 143 to the rod 137. At its opposite end the shaft 137 is clutched by means of a 85 removable clutch element 145 held by a machine screw 146 to the element 139. The hand wheel 141 is clutched by clutch teeth 149 to a clutch portion 150 on a member 138. It will be readily apparent that it is 90 possible to interchange the handles 140 and 141 and related parts and the element 146 so that the elements 135 and 136 may be controlled from the right hand side of the machine by the elements 140 and 141 respectively. 95

At either side of the front end of the machine frame there is provided a swiveled rotatable flexible feeding member guiding element 151. Each of these is mounted upon 100 an arm 152 which is journaled upon a shaft 153 about which it may be swung so as to bring its respective sprocket always near the bottom of the machine irrespective of whether the machine is slid upon the surface 105 2 or the surface 3. Spring controlled locking means 154 serves to hold the element 152 in one position, but on reversal of the position of the parts it will be evident that the locking means may still cooperate, but 110 then with an opening 156, in holding the parts in their new position. The member 152 engages suitable stops 157 in either of its positions. A suitable chain stripper or guiding element is provided at 158 and this 115 may be placed at either side of the machine as is desirable for the purpose of stripping the chain from the sprocket 11 or 12, whichever is operating as the feed sprocket at the time. Noting Figs. 1 and 2, it will be 120 observed that in cutting from right to left the flexible feeding member extends from a suitable jack or takeup member (not shown) adjacent the left hand rib, back around the sprocket 151 at the left hand side 125 of the machine, rearwardly about the sprocket 11 from below, then forwardly over the top of the sprocket and over the chain stripper 158 in the form of a loop and next around inside one of a pair of corner sprock- 130

ets 159 rotatable on vertical axes at the rear of the frame, then in contact with a central sprocket 160, then inside the other sprocket 159, then forward over the top of the sprocket 12, then backward from the lower side of the sprocket 12, around a sprocket 161 coaxial with the right hand sprocket 159 and then off to a suitable jack or takeup member (not shown) at the left hand rib. It is to be observed that the sprockets 159 and 161 are alike at either side of the machine and that the rear of the frame is curved as at 163 to guide the slack intermediate portion of the flexible feeding member. The reeve 15 is reversed in cutting from right to left and a different reeve is also used when the machine is cutting while sliding upon the surface 2, as might be the case in cutting out a dirt band. An opening 164 is provided 20 in the rear end of the frame to permit access of a driven element carried by a mining machine truck to the gear 26 so that the latter may constitute a truck driving member. Suitable electrical controlling mechanism 25 (not shown) is mounted in the spaces designated controller and resistance.

The general mode of operation of this mechanism will already be apparent. Either the element 91 or the element 92 may be employed to drive the differential and with the use of one of these elements there will be fast rotation in one direction while with the use of the other there will be a slower rotation in the opposite direction. In view of the fact that both the sprockets 11 and 12 tend to rotate in the same direction and the further fact that the element 12 tends to rotate due to the pull of the tail chain, it will be apparent that it is necessary to rather 35 heavily load the brake band 118 during cutting from right to left so that the member 102 will not be more rapidly turned than the member 101. By varying the tension of this member it is of course possible to 40 produce angling of the machine. The machine may be caused to cut from left to right by reversing the functions of the feed operating members 11 and 12 and the controls can be changed to the right hand side of 45 the machine for convenience during this operation.

While I have in this application specifically described one form which my invention may assume in practice, it will be understood that this form of the same is shown 50 for purposes of illustration and that the invention may be modified and embodied in other forms without departing from its spirit or the scope of the appended claims.

What I claim as new and desire to secure by Letters Patent is:

1. The combination with a mining machine, of a feed driving mechanism thereon including a differential, feed operating members connected to different elements of said

differential, means controlling the rotation of said members, and a plurality of worm drives for said differential.

2. The combination with a mining machine, of a feed driving mechanism thereon including a differential, feed operating members thereon connected to different elements of said differential, and means for controlling the direction of rotation of said members including a plurality of worm drives 75 for said differential.

3. The combination with a mining machine, of a feed driving mechanism thereon including a differential having at least one orbitally movable element, means for moving said orbitally moving element through its orbit in different directions including oppositely rotating elements adapted to move the same directly, and feed operating members connected to different elements of the 85 differential.

4. The combination with a mining machine, of a feed driving mechanism thereon including a differential having at least one orbitally movable element, means for moving said orbitally moving element through its orbit in different directions including oppositely rotating elements adapted to move the same directly, feed operating members connected to different elements of the differential, and means for retarding either of 95 said members.

5. In a mining machine, the combination including a differential including coaxial elements and at least one orbitally moving 100 element operatively engaging said coaxial elements, means for causing said last mentioned element to traverse its orbit in opposite directions including oppositely rotating elements coaxial with said first mentioned coaxial elements, and feed operating members connected to said first mentioned coaxial 105 elements.

6. In a mining machine, the combination including a differential including coaxial elements and at least one orbitally moving 110 element operatively engaging said coaxial elements, means for causing said last mentioned element to traverse its orbit in opposite directions at different speeds including oppositely rotating elements coaxial with said first mentioned coaxial elements, and feed operating members connected to said first mentioned coaxial 115 elements.

7. In a mining machine, the combination including a differential including coaxial elements and at least one orbitally moving element operatively engaging said coaxial elements, means for causing said last mentioned element to traverse its orbit in opposite directions including oppositely rotating elements coaxial with said first mentioned coaxial elements, feed operating members connected to said first mentioned coaxial 120 elements, and means for frictionally retard- 125

ing the rotation of said feed operating members.

8. A mining machine, the combination including a flexible feeding means including a plurality of flexible feeding portions extending oppositely from the opposite ends of the machine frame during cutting across a face, rotatable members operatively engaging said portions and respectively operative when rotated in the proper direction to draw in the portions with which they cooperate and mechanism for controlling the rotation of said members including a plurality of coaxial elements, a plurality of which provide coaxial portions and one of which provides orbitally moving means which constitutes a connecting means between said coaxial portions, operative connections between one of said coaxial elements and one of said rotatable members, distinct operative connections between the other of said coaxial elements and the other of said members, and means for effecting travel of said orbitally moving means at different speeds through its orbit including motor driven elements coaxial with said coaxial elements and selectively connectible in driving relation with that coaxial element which provides the orbitally moving means.

9. A mining machine, the combination including a flexible feeding means including a plurality of flexible feeding portions extending oppositely from the opposite ends of the machine frame during cutting across a face, rotatable members operatively engaging said portions and respectively operative when rotated in the proper direction to draw in the portions with which they cooperate, and mechanism for controlling the rotation of said members including a plurality of coaxial elements, a plurality of which provide coaxial portions and another of which provides orbitally moving means which constitutes a connecting means between said coaxial portions, operative connections between one of said coaxial elements and one of said rotatable members, distinct operative connections between another of said coaxial elements and another of said members, and means for effecting travel of said orbitally moving means in opposite directions through its orbit including motor driven elements coaxial with said coaxial elements and selectively connectible in driving relation with that coaxial element which provides the orbitally moving means.

10. A mining machine, the combination including a flexible feeding means including a plurality of flexible feeding portions extending oppositely from the opposite ends of the machine frame during cutting across a face, rotatable members operatively engaging said portions and respectively operative when rotated in the proper direction to draw in the portions with which they co-

operate, and mechanism for controlling the rotation of said members including a plurality of coaxial elements, a plurality of which provide coaxial portions and one of which provides orbitally moving means which constitutes a connecting means between said coaxial portions, operative connections between one of said coaxial elements and one of said rotatable members, distinct operative connections between the other of said coaxial elements and the other of said members, and means for effecting travel of said orbitally moving means at different speeds and in opposite directions through its orbit including motor driven elements coaxial with said coaxial elements and selectively connectible in driving relation with that coaxial element which provides the orbitally moving means.

11. In a mining machine, the combination including a flexible feeding means including a plurality of flexible feeding portions extending oppositely from the opposite ends of the machine frame during cutting across a face, rotatable members operatively engaging said portions and respectively operative when rotated in the proper direction to draw in the portions with which they cooperate, and mechanism for controlling the rotation of said members including a plurality of coaxial elements, a plurality of which provide coaxial portions and one of which provides orbitally moving means which constitutes a connecting means between said coaxial portions, operative connections between one of said coaxial elements and one of said members, distinct operative connections between another of said elements and the other of said members, and means for effecting travel of said orbitally moving means at different speeds through its orbit including motor driven elements coaxial with said coaxial elements and selectively connectible in driving relation with that coaxial element which provides the orbitally moving means, and means for retarding the rotation of either of said coaxial elements positively connected with said rotatable members.

12. A mining machine, the combination including a flexible feeding means including a plurality of flexible feeding portions extending oppositely from the opposite ends of the machine frame during cutting across a face, rotatable members operatively engaging said portions and respectively operative when rotated in the proper direction to draw in the portions with which they cooperate, and mechanism for controlling the rotation of said members including a plurality of coaxial elements, a plurality of which provide coaxial portions and another of which provides orbitally moving means which constitutes a connecting means between said coaxial portions, operative connections between one of said coaxial elements and one of said members, distinct operative connections between another of said elements and the other of said members, and means for effecting travel of said orbitally moving means at different speeds through its orbit including motor driven elements coaxial with said coaxial elements and selectively connectible in driving relation with that coaxial element which provides the orbitally moving means, and means for retarding the rotation of either of said coaxial elements positively connected with said rotatable members.

one of said coaxial elements and one of said members, distinct operative connections between another of said elements and the other of said members, and means for effecting travel of said orbitally moving means in opposite directions through its orbit including motor driven elements coaxial with said coaxial elements and selectively connectible in driving relation with that coaxial element which provides the orbitally moving means, and means for retarding the rotation of either of said coaxial elements positively connected with said rotatable members.

13. A mining machine, the combination including a flexible feeding means including a plurality of flexible feeding portions extending oppositely from the opposite ends of the machine frame during cutting across a face, rotatable members operatively engaging said portions and respectively operative when rotated in the proper direction to draw in the portions with which they co-operate, and mechanism for controlling the rotation of said members including a plurality of coaxial elements, a plurality of which provide coaxial portions and another of which provides orbitally moving means which constitutes a connecting means between said coaxial portions, operative connections between one of said coaxial elements and one of said members, distinct operative connections between another of said elements and another of said members, and means for effecting travel of said orbitally moving means at different speeds and in opposite directions through its orbit including motor driven elements coaxial with said coaxial elements and selectively connectible in driving relation with that coaxial element which provides the orbitally moving means.

14. In a mining machine, feeding mechanism including a plurality of worms of different pitch, worm wheels driven thereby, a differential including coaxial elements providing coaxial portions and a third element providing at least one orbitally moving element connecting said first and second mentioned elements of said differential, feed operating members operatively connected with said first and second mentioned elements of said differential, and means for clutching the third mentioned element of said differential to either of said worm wheels.

15. In a mining machine, feeding mechanism including a plurality of oppositely rotating worms, worm wheels driven thereby, a differential including coaxial elements providing coaxial portions and a third element providing at least one orbitally moving element connecting said first and second mentioned elements of said differential, feed operating members operatively connected with said first and second mentioned elements of said differential, and means for

clutching the third mentioned element of said differential to either of said worm wheels.

16. In a mining machine, feeding mechanism including a plurality of oppositely rotating worms of different pitch, worm wheels driven thereby, a differential including coaxial elements providing coaxial portions and a third element providing at least one orbitally moving element connecting said first and second mentioned elements of said differential, feed operating members operatively connected with said first and second mentioned elements of said differential, and means for clutching the third mentioned element of said differential to either of said worm wheels.

17. In a mining machine, feeding mechanism including a plurality of worms of different pitch, worm wheels driven thereby, a differential including coaxial elements providing coaxial portions and a third element providing at least one orbitally moving element connecting said first and second mentioned elements of said differential, feed operating members operatively connected with said first and second mentioned elements of said differential, and means for clutching the third mentioned element of said differential to either of said worm wheels including clutch mechanism coaxial with said coaxial differential elements.

18. In a mining machine, feeding mechanism including a plurality of oppositely rotating worms, worm wheels driven thereby, a differential including coaxial elements providing coaxial portions and a third element providing at least one orbitally moving element connecting said first and second mentioned elements of said differential, feed operating members operatively connected with said first and second mentioned elements of said differential, and means for clutching the third mentioned element of said differential to either of said worm wheels including clutch mechanism coaxial with said coaxial differential elements.

19. In a mining machine, feeding mechanism including a plurality of oppositely rotating worms of different pitch, worm wheels driven thereby, a differential including coaxial elements providing coaxial portions and a third element providing at least one orbitally moving element connecting said first and second mentioned elements of said differential, feed operating members operatively connected with said first and second mentioned elements of said differential, and means for clutching the third mentioned element of said differential to either of said worm wheels including clutch mechanism coaxial with said coaxial differential elements.

20. In a mining machine, feeding mechanism including a plurality of worms of dif-

ferent pitch, worm wheels driven thereby, a differential including coaxial elements providing coaxial portions and a third element providing at least one orbitally moving element connecting said first and second mentioned elements of said differential, feed operating members operatively connected with said first and second mentioned elements of said differential, means for clutching the third mentioned element of said differential to either of said worm wheels including clutch mechanism coaxial with said coaxial differential elements, and operating means for said clutch projecting axially through said differential and operable from either end thereof.

21. In a mining machine, feeding mechanism including a plurality of oppositely rotating worms, worm wheels driven thereby, a differential including coaxial elements providing coaxial portions and a third element providing at least one orbitally moving element connecting said first and second mentioned elements of said differential, feed operating members operatively connected with said first and second mentioned elements of said differential, means for clutching the third mentioned element of said differential to either of said worm wheels including clutch mechanism coaxial with said coaxial differential elements, and operating means for said clutch projecting axially through said differential and operable from either end thereof.

22. In a mining machine, feeding mechanism including a plurality of oppositely rotating worms of different pitch, worm wheels driven thereby, a differential including coaxial elements providing coaxial portions and a third element providing at least one orbitally moving element connecting said first and second mentioned elements of said differential, feed operating members operatively connected with said first and second mentioned elements of said differential, means for clutching the third mentioned element of said differential to either of said worm wheels including clutch mechanism coaxial with said coaxial differential elements, and operating means for said clutch projecting axially through said differential and operable from either end thereof.

23. In a mining machine, a pair of coaxial feed operating members, friction braking means associated with said members, a differential intermediate said members and having corresponding elements connected to said feed operating members and having at least one orbitally moving element cooperating with said corresponding elements and adapted to drive the same, and means for effecting orbital movement of said last mentioned element in opposite directions including reversely rotating elements coaxial with said feed operating members and selectively

connectable to the third mentioned differential element.

24. The combination with a mining machine, of a feed driving mechanism thereon including a differential having an orbitally movable element, feed operating members connected to different elements of said differential, means controlling the rotation of said feed operating members, and a plurality of worm drives for said orbitally movable element.

25. The combination with a mining machine, of a feed driving mechanism thereon including a differential having an orbitally movable element, feed operating members connected to different elements of said differential, and means for controlling the direction of rotation of said members including a plurality of worm drives for said orbitally movable element.

26. The combination with a mining machine, of a feed driving mechanism thereon including a differential having at least one orbitally movable element, means for moving said orbitally movable element through its orbit in different directions including oppositely rotating worm gears adapted to move the same directly, and feed operating members connected to different elements of said differential.

27. The combination with a mining machine, of a feed driving mechanism thereon including a differential having at least one orbitally movable element, means for moving said orbitally movable element through its orbit in different directions including oppositely rotating worm gears adapted to move the same directly, and feed operating members connected to different elements of said differential, and means for retarding either of said members.

28. In a mining machine, the combination including a differential including coaxial elements and at least one orbitally movable element operatively engaging said coaxial elements, means for causing said last mentioned element to traverse its orbit in opposite directions including oppositely rotating worm gears coaxial with said coaxial element, and feed operating members connected to said coaxial elements.

29. In a mining machine, the combination including a differential including coaxial elements and at least one orbitally movable element operatively engaging said coaxial elements, means for causing said last mentioned element to traverse its orbit in opposite directions at different speeds including oppositely rotating worm gears coaxial with said coaxial elements, and feed operating members connected to said coaxial elements.

30. In a mining machine, the combination including a differential including coaxial elements and at least one orbitally movable

- element operatively engaging said coaxial elements, means for causing said last mentioned element to traverse its orbit in opposite directions at different speeds including oppositely rotating worm gears coaxial with said coaxial elements, feed operating members connected to said coaxial elements, and means for frictionally retarding the rotation of said feed operating members.
31. In a mining machine, feeding mechanism including a plurality of flexible feeding portions, a differential including an orbitally movable element, a plurality of feed operating members operatively connected to said differential and cooperating respectively with said flexible portions, and a plurality of worm gears of different pitch alternatively operative to drive said orbitally movable element at different speeds.
32. In a mining machine, feeding mechanism including a plurality of flexible feeding portions, a differential including an orbitally movable element, a plurality of feed operating members operatively connected to said differential and cooperating respectively with said flexible portions, and a plurality of worm gears of different pitch alternatively operative to drive said orbitally movable element at different speeds and in opposite directions.
33. In a mining machine, feeding mechanism including a plurality of flexible feeding portions, a differential including an orbitally movable element, a plurality of feed operating members operatively connected to said differential and cooperating respectively with said flexible portions, a plurality of worm gears of different pitch alternatively operative to drive said orbitally movable element at different speeds, and intermeshing spur gears operatively connecting said worm gears with one another.
34. In a mining machine, feeding mechanism including a plurality of flexible feeding portions, a differential including an orbitally movable element, a plurality of feed operating members operatively connected to said differential and cooperating respectively with said flexible portions, said feed operating members being arranged for rotation on axes lying in the same straight line, and a plurality of worm gears of different pitch alternatively operative to drive said orbitally movable element at different speeds.
35. In a mining machine, feeding mechanism including a plurality of flexible feeding portions, a differential including an orbitally movable element, a plurality of feed operating members operatively connected to said differential and cooperating respectively with said flexible portions, said feed operating members being arranged for rotation on axes lying in the same straight line, and a plurality of worm gears of different pitch alternatively operative to drive said orbitally movable element at different speeds and in opposite directions.
36. In a mining machine, feeding mechanism including flexible feeding means including a plurality of flexible feeding portions, a differential, a plurality of worm gears rotatable on axes parallel to the same straight line and selectively operative as driving members for said differential, and a plurality of feed operating members cooperating respectively with said feeding portions and alternatively connectible with said worm gears.
37. In a mining machine, feeding mechanism including flexible feeding means including a plurality of flexible feeding portions, a differential, a plurality of worm gears rotatable on axes parallel to the same straight line and selectively operative as driving members for said differential, and a plurality of feed operating members cooperating respectively with said feeding portions and selectively connectible with said worm gears, said feed operating members rotating on axes lying in the same straight line.
38. In a mining machine, feeding mechanism including flexible feeding means including a plurality of flexible feeding portions, a differential, a plurality of worm gears rotatable on axes parallel to the same straight line and selectively operative as driving members for said differential, and a plurality of feed operating members cooperating respectively with said feeding portions and selectively connectible with said worm gears, said feed operating members rotating on axes lying in the same transversely extending straight line.
39. The combination with a mining machine, of feeding mechanism thereon including a differential including an orbitally movable element, feed operating members connected to different elements of said differential, and driving means for said feed operating members including a plurality of drive trains having coaxial terminal elements alternatively connectible to said orbitally movable element.
40. The combination with a mining machine, of feeding mechanism thereon including a differential including an orbitally movable element, feed operating members connected to different elements of said differential, and driving means for said feed operating members including a plurality of drive trains having coaxial terminal elements rotatable in opposite directions and alternatively connectible to said orbitally movable element.
41. The combination with a mining machine, of feeding mechanism thereon including a differential including an orbitally movable element, feed operating members connected to different elements of said differential.

- ential, and driving means for said feed operating members including a plurality of drive trains having coaxial terminal elements rotatable at different speeds and in opposite directions and alternatively connectible to said orbitally movable element.
42. The combination with a mining machine, of feeding mechanism thereon including a differential including an orbitally movable element, feed operating members connected to different elements of said differential, and driving means for said feed operating members including a plurality of drive trains having coaxial terminal elements rotatable at different speeds and in opposite directions and alternatively connectible to said orbitally movable element, and means for controlling rotation of said feed operating members.
43. In a mining machine, feeding mechanism including fast and slow speed transmission gear trains, a differential driven thereby, a plurality of feed operating members connected to elements of said differential, and means for alternatively connecting said fast and slow speed gear trains to said differential including a controlling clutch, and operating means therefor extending coaxially through said differential.
44. In a mining machine, feeding mechanism comprising a differential including coaxial elements and a cooperating orbitally movable element, driving gearing therefor operatively connected to said differential including terminal elements, a plurality of feed operating members operatively connected to said coaxial elements respectively, and means for alternatively connecting said terminal elements to said differential including a controlling clutch, and operating means therefor extending coaxially through said coaxial elements of said differential.

In testimony whereof I affix my signature.
MORRIS P. HOLMES.
